UNITED STATES PATENT OFFICE

126,416

DESIGN FOR A JEWELRY COMPONENT OR THE LIKE

Florence N. Lewis, New York, N. Y.

Application October 26, 1940, Serial No. 96,104

Term of patent 14 years

To all whom it may concern:

Be it known that I, Florence N. Lewis, a citizen of the United States, residing at New York city, in the county of New York and State of New York, have invented a new, original, and ornamental Design for a Jewelry Component or the like, of which the following is a specification, reference being had to the accompanying drawing, forming part thereof.

In the drawing:

Fig. 1 is a front elevational view of a jewelry component or the like showing my new design;
Fig. 2 is a side elevation thereof;
Fig. 3 is a rear elevational view.

I claim:

The ornamental design for a jewelry component or the like, as shown.

FLORENCE N. LEWIS.
